CHILD'S WHEELED TOY

Erkki Ruokonen, Helsinki, Finland, assignor to
Aarikka-Koru, Helsinki, Finland

Filed Aug. 31, 1970, Ser. No. 24,776

Term of patent 14 years

Int. Cl. D21—01

U.S. Cl. D34—15

FIG. 1 is a side perspective view of a child's wheeled toy showing my new design;

FIG. 2 is a top plan view thereof;

FIG. 3 is a bottom plan view thereof;

FIG. 4 is a rear elevational view thereof.

I claim:

The ornamental design for a child's wheeled toy, as shown.
